UNITED STATES PATENT OFFICE.

HERBERT LUDLOW, OF BROOKLYN, ASSIGNOR TO WILLIAM H. H. ROGERS,
OF NEW YORK, N. Y.

FOLDING BOX.

SPECIFICATION forming part of Letters Patent No. 267,698, dated November 21, 1882.

Application filed April 5, 1882. (No model.)

To all whom it may concern:

Be it known that I, HERBERT LUDLOW, of Brooklyn, in the county of Kings and State of New York, have invented a new and useful 5 Improvement in Folding Boxes, of which the following is a full, clear, and exact description.

My invention consists of a folding or collapsible box of improved construction, and of an improved box-cover, the construction of the box 10 being such that the waste of material in its manufacture is very small, and such that the box can be easily and quickly set up for use, the construction of the cover being such that it can be made of one piece of material, and such that any 15 number of covers may be set one within another, so that they may be packed away in small space. The form of box which I prefer will be a four-cornered box made with the lock at the bottom of the box and open at the top, 20 the sides or walls of the box being continuous or solid, the same as ordinary non-folding boxes. The rim of the covers will be made to stand slightly outward or flaring from the main portion on top of the cover, and the top of the 25 box will be slightly cut away at the corners in such manner that the flaring covers will fit upon the box.

Reference is to be had to the accompanying drawings, forming a part of this specification, 30 in which similar letters of reference indicate corresponding parts in all the figures.

Figure 1 is a plan view of the box as it appears when folded. Fig. 2 is a sectional elevation of the same, taken on the line $x-x$ of Fig. 35 1. Fig. 3 is a perspective view of the box inverted, as it appears when set up for use. Fig. 4 is a plan view of the box-cover; and Fig. 5 is a sectional elevation, illustrating several 40 covers as they appear when set into each other for packing or stowing away.

A represents the folding box, and B represents the cover.

In making my new and improved folding box A, I prefer to take a rectangular piece of material of suitable size and unite its ends so 45 as to practically form a cylindrical blank. This blank will then be brought together or collapsed, as shown in Fig. 2, so as to form the bends or folds $a-a'$. The blank is then to

be bent or again folded on opposite sides to 50 form the bends or folds $b-b'$, which are made equidistant from the bends $a-a'$, respectively. If a square box is desired, these bends or folds $b-b'$ will be made in the center of the width of the blank (midway between the bends $a-a'$) as 55 folded. If a rectangular box is desired, these folds $b-b'$ will be made on opposite sides of the center of the folded blank, as shown in Fig. 1, the distance from the center being varied according to the desired relative width of the 60 sides and ends of the box. The blank is then cut through with the slots or cuts $c-c'$ and $d-d'$ in all of the bends or folds, the slots or cuts extending from one edge of the blank to or nearly to the horizontal center, or center of the length of the 65 blank, thus forming the flaps D, E, F, and G. The flap G is then cut through at or near the center with the slot or cut h , which reaches to or nearly to the center of the width of the blank, and its corners are diagonally cut to form the 70 locking-heads $j-j$, as clearly shown in Fig. 1 and in dotted lines in Fig. 3, and the flap F is incised to form the locking-slot k , as shown in Fig. 3 and in dotted lines in Fig. 1. The flaps D, E, F, and G are then bent or folded at the center of 75 the width of the blank to form the folds $f-f'$ and $g-g'$.

To set the box up, the flaps D and E are first folded in, as shown in Fig. 3. The flap F is then folded in, and then one of the heads j is 80 passed through the slot k , and then, finally, the other, the heads, after passing through the slot, being drawn to one side to complete the lock.

The cover B is made of a single piece of material, and the rims pp thereof are made slightly flaring, as shown clearly in Figs. 4 and 5, so that the covers are adapted to be set one into another, as shown in Fig. 5, so that many covers can be packed or stowed away in small space. 85

In order to make the cover fit upon the box, the corners of the box are slightly cut away at the top of the box, as shown at ll , so that the upper edges of the box will conform to the inclination of the cover. 90

By this construction of the box it will be seen that the box is very simple, quickly and easily set up, has but one fastening or lock, is 95

continuous or solid at its sides, and is open at the top like ordinary boxes, and that the waste of material in the manufacture of the box is reduced to the minimum for making a complete, strong, and perfect box. It will be seen that the flaps D and E serve only to close the bottom of the box at two of the corners, and to strengthen the bottom of the box, and that they might be omitted in small boxes or boxes 10 intended for light use, and thus effect a still further saving in material.

Although I prefer to make the box so that the lock is formed upon the bottom of the box, I do not confine myself to such construction, 15 as the box may be formed so that the lock will come on the side of the box.

Having thus fully described my invention, I

claim as new and desire to secure by Letters Patent—

1. A folding-box blank formed with the flaps 20 G and F, the flap G being cut to form the locking-heads *j j*, and the flap F being formed with the slot *k*, substantially as described.

2. A blank for a folding box, bent to form the folds *a a'*, *b b'*, *f f'*, and *g g'*, and cut to form 25 the flaps D, E, F, and G, the flap G being centrally slotted and formed with the locking-heads *j j*, and the flap F cut to form the slot *k*, substantially as described.

HERBERT LUDLOW.
